ATTORNEY

UNITED STATES PATENT OFFICE.

EDWARD B. JACOBSON, OF PITTSFIELD, MASSACHUSETTS, ASSIGNOR TO J AND B MANUFACTURING COMPANY, OF PITTSFIELD, MASSACHUSETTS, A CORPORATION OF MASSACHUSETTS.

IGNITION-TIMER.

1,213,495.

Specification of Letters Patent. Patented Jan. 23, 1917.

Application filed December 18, 1915. Serial No. 67,685.

To all whom it may concern:

Be it known that I, EDWARD B. JACOBSON, a citizen of the United States, residing at Pittsfield, in the county of Berkshire and 5 State of Massachusetts, have invented certain new and useful Improvements in Ignition-Timers, of which the following is a specification.

This invention relates to apparatus for 10 regulating the time of ignition or sparking in internal combustion engines.

Apparatus of the class described commonly includes an internal rotary portion adapted to make and break a succession of 15 low tension primary circuits, corresponding to the number of engine cylinders and an adjustable housing portion for inclosing the rotary portion and carrying contacts for successive contact by the rotary portion and 20 arranged in the several circuits.

The present invention has for its object the provision of improved means for the introduction of a lubricant into the shell or housing portion of the timer apparatus.

25 To this end the invention consists in the construction, combination and arrangement of parts as hereinafter described and claimed, reference being had to the accompanying drawings illustrating a preferred form of 30 embodiment of the invention, and wherein—

Figure 1 is a side view of an approved form of ignition timer, with my device operatively mounted on the housing portion thereof, the relative position of the oil cap or cover when lifted being indicated in dotted lines; Fig. 2, a front view of the same, a portion of the timer housing being 35 cut away to disclose the inclosed rotary portion; and Fig. 3, a detail view of the oil opening provided in the timer housing.

As shown the rotary portion 1 of the timer device is mounted to move with a cam-shaft 2 which is supposed to be geared to the main engine shaft (not shown) in the usual manner. The rotary portion 1 is arranged to 45 contact with the lower end of one or more terminals 3, 3, etc. mounted exteriorly on the shell or housing 4, and extending through the shell into the interior of the housing, the 50 lower ends of the terminals (not shown) being usually terminated in appropriate contacts embedded on the inner surface of an insulation ring 5 within the housing over which the rotary portion travels.

55 The rotary adjustment of the housing 4

with relation to the inclosed rotary portion 1 is controlled by an arm in the form of an upright plate 6 mounted exteriorly of the housing on the upper side thereof, the arm or plate being provided at the lower end 60 with spaced feet 7, 7, inclined forward and downward at an angle to the body of the plate and suitably secured to the housing by rivets 8, 8. The plate 6 is provided at its upper end with a transverse opening 9 to receive a bushing 10 mounted therein as a convenient form of support for the detachable connection of a control rod (not shown).

As shown, in combination with the control-arm or plate 6, I provide an oil cap or 70 cover 11, to protect an opening 19, (Fig. 3) provided through the wall of the housing 4 at a point somewhat below the base of the plate 6, said opening being provided for the introduction of oil or other lubricant into 75 the interior of the housing for the lubrication of the rotary portion 1 and the traveled surface of the ring 5. The cover 11 is constructed in the form of a flat plate preferably reduced in width at its forward end 80 which is curved slightly upward to form a convenient lip 12 by which to raise the cover from its normal position. The cover is hinged at its rear end to the plate 6 by means of parallel spaced rearward extensions in the 85 form of loops or eyes 13, 13, arranged to pivot upon a bar 14 carried by upright eye-butt 15, 15, provided at opposite points on the feet 7, 7, the upward displacement of the cover being yieldingly opposed by a coil 90 spring 16 mounted centrally on the bar 14, the ends 17, 17, of the spring being extended laterally in opposite directions to bear inward upon the plate 6 and the cover 11.

In normal position the cover 11 is evenly 95 seated over the oil inlet 19 to exclude the admission of dirt, an annular seat in the form of a hollow rivet 18 extending slightly above the surrounding surface of the housing 4 being preferably provided around the margin 100 of the inlet.

The cover 11 constructed as herein shown forms an ample dust-proof cap for the protection of the inlet 19 and readily lends itself to displacement when lubrication of the 105 timer is required, such displacement being accomplished by the introduction of a finger or of the funnel of the oil-can under the lip 12.

One of the advantages of an oil inlet and 110

cover constructed for use in connection with an ignition timer, in accordance with my invention, is a free and unobstructed passage for lubricant introduced into the interior of the housing. A further advantage is the form of cover or closure to the oil inlet, which readily admits of displacement for oiling purposes but does not permit dirt to become wedged or forced into the opening.

10 I claim:

1. In an ignition timer, the combination with a rotary portion, of an adjustable housing for inclosing the rotary portion and having a transverse opening therethrough, an upright arm secured at its lower end to the exterior of the housing and having a free end for detachable connection with a control rod, a plate pivoted at its rear end to said arm and seated over said opening, and spring means for yieldingly opposing the upward displacement of the plate.
- 20 2. In an ignition timer, the combination

with a rotary portion, of a housing for inclosing the rotary portion and having a transverse opening through its face, an annular seat 25 provided on the housing around said opening and extending above the surface of the housing, an upright arm secured to the exterior of the housing adjacent said opening and having a free upper end for detachable connection with a control rod, a bar mounted on said arm at its lower end, a plate pivoted at its rear end on said bar and seated on said seat over said opening and having its forward end inclined away from the housing, and a spring carried on said bar and arranged to yieldingly oppose the upward displacement of the plate.

In testimony whereof I hereunto affix my signature in presence of two witnesses.

EDWARD B. JACOBSON.

Witnesses:

FLOYD A. KNIGHT,
JOHN J. WHITTLESEY.
